UNITED STATES PATENT OFFICE.

TIMOTHY F. COLLINS, OF MERIDEN, CONNECTICUT.

MUSIC-ROLL.

SPECIFICATION forming part of Letters Patent No. 761,449, dated May 31, 1904.

Application filed July 20, 1903. Serial No. 166,211. (No model.)

To all whom it may concern:

Be it known that I, TIMOTHY F. COLLINS, a citizen of the United States, residing at Meriden, in the county of New Haven and State of Connecticut, have invented certain new and useful Improvements in Music-Rolls, of which the following is a specification.

This invention relates to music-rolls generally employed for the reception of perforated paper record-sheets which are wound thereon and are ordinarily used in connection with mechanically-played musical instruments, and has for one of its objects the provision of such an article which shall be light in weight and sufficiently strong and rigid in action.

My invention has, furthermore, for its object the combination, with the body portion of the roll, of removable heads, which may be secured to the ends thereof when the roll is to be placed in the instrument, while they may be removed therefrom, thus leaving the roll, with the record wound thereon, in the shape of a plain cylinder without any projections, so that a number thereof may be packed without making especial preparations in protecting the heads and the trunnions projecting therefrom, such as may be found in devices of this kind heretofore in use.

Further objects of my invention may be found in the peculiar construction of some of the parts, as will be hereinafter described, and particularly pointed out in the claims.

In the accompanying drawings, in which similar characters denote similar parts, Figure 1 represents a central longitudinal section of a roll made in accordance with my invention. Fig. 2 is a similar section of the roll-body, taken on a plane at right angles to that of Fig. 1. Fig. 3 is an end view thereof. Fig. 4 shows one of the roll-heads detached, and Fig. 5 illustrates one of the head-locking members or plugs in detail.

As above stated, it is one of the objects of my invention to provide a music-roll the heads for which may be inserted and removed when desired, so that one pair of heads furnished for an instrument will be sufficient, and consequently the cost of furnishing rolls for use in connection with such heads will be reduced, an item which is of considerable

importance when it is considered that thousands upon thousands of such rolls are employed and new records are constantly making their appearance.

My improved roll comprises a tubular body 55 10, preferably made of pasteboard or equivalent material and chambered or open at both ends to receive the shank portions 11 12 of flanged heads 13 14, respectively. The heads 13 14 are of such diameter as to accommodate 60 or receive between them record or music strips wound upon any roll-body 10, and the shank portions 11 and 12 fit into the tube, so as to be readily inserted or removed therefrom, their lengths being such as to afford a 65 substantial support for each end of the roll.

The heads 13 14 are preferably provided with shoulders 15 16, whereby the roll is held against longitudinal movement in the instrument, and trunnions 17 18 are secured to said 70 heads and serve as journals for the roll, one of said trunnions 18 having wings 19, whereby the head 14 may be brought into rotative connection with the rewinding mechanism of the instrument, as usual. Means are provided 75 for locking the heads 13 14 against rotation in the body 10, so that the supporting fit between the shanks 11 and 12 and the tube 10 may be preserved, these means comprising 80 plugs 20, secured to the tube 10 at a short distance from its ends and having in the preferred form thereof shown diametrical slots 21, adapted to receive corresponding tenons 22, secured to or forming part of said shanks 11 12. Other forms of clutch-surfaces may, 85 however, be employed without departure from the invention.

Changes may be made in the particular organization and construction of the several parts of my improved roll, the invention not 90 being limited to the precise construction shown.

Having thus described my invention, what I claim is—

1. The combination, with a tubular body 95 portion, of plugs carried by said body portion; and removable, flanged heads having shanks fitting into the ends of said tubular body portion, and each having a clutch member for engaging said plugs.

2. The combination, with a tubular body portion, of plugs carried by said body portion, and each having a slot; removable, flanged heads having shank portions fitting into the ends of said tube, and each having a clutch member for entering the slot of the plug.

3. A roll comprising a tubular body portion provided with interior plugs each having a clutch-surface; and removable heads, each having a shank provided with a clutch-surface adapted to engage the clutch-surface of the plug.

4. A music-roll comprising a tubular body,

and plugs, each having a clutch-surface, with-
in said body.

5. A music-roll comprising a tubular body having slotted plugs, and detachable heads each having a shank provided with a tenon for engaging the slotted plug with which it is connected.

In testimony whereof I affix my signature in presence of two witnesses.

TIMOTHY F. COLLINS.
